(57) **CLAIM**

The ornamental design for an interchangeable lens for a head mounted device, as shown and described.

DESCRIPTION

FIG. 1 is a front and right side perspective view of a first embodiment of an interchangeable lens for a head mounted device;

FIG. 2 is a front view thereof;

FIG. 3 is a left side view thereof;

FIG. 4 is a right side view thereof;

FIG. 5 is a right side perspective view thereof;

FIG. 6 is an enlarged view of a portion of the right side thereof, indicated by a dash-dot broken line in FIG. 5;

FIG. 7 is a rear and left side perspective view thereof;

FIG. 8 is a front and right side perspective view thereof;

FIG. 9 is a rear view thereof;

FIG. 10 is a rear and inverted view thereof;

FIG. 11 is a bottom view thereof;

FIG. 12 is a right view thereof;

FIG. 13 is a top view thereof;

FIG. 14 is a front view thereof; and,

FIG. 15 is a front and left perspective view thereof.

The dashed broken lines shown are included for the purpose of illustrating unclaimed portions of the interchangeable lens for a head mounted device and form no part of the claimed design. The dash-dot broken lines in FIGS. 5 and 6 are for the purpose of indicating the boundaries of the enlarged area shown in FIG. 6, and form no part of the claimed design.
